WASTEBASKET OR SIMILAR ARTICLE

Nathan W. Roop, Columbus, Ohio, assignor to Columbus Plastic Products, Inc., Columbus,
Ohio, a corporation of Ohio

Application January 24, 1952, Serial No. 18,189

Term of patent 14 years

(Cl. D58—17)

To all whom it may concern:

Be it known that I, Nathan W. Roop, a citizen of the United States, residing at Columbus, in the county of Franklin and State of Ohio, have invented a new, original, and ornamental Design for a Wastebasket or Similar Article, of which the following is a specification, reference being had to the accompanying drawing, forming a part thereof.

Fig. 1 is a top plan view of a wastebasket or similar article showing my new design;

Fig. 2 is a side elevational view;

Fig. 3 is an end elevational view;

Fig. 4 is a bottom plan view;

Fig. 5 is a perspective view taken on a reduced scale; and

Fig. 6 is a fragmentary vertical sectional view taken through an end wall along a plane indicated by the line 6—6 of Fig. 1.

I claim:

The ornamental design for a wastebasket or similar article, substantially as shown.

NATHAN W. ROOP.
